UNITED STATES PATENT OFFICE.

THOMAS C. WHITE, OF ST. LOUIS, MISSOURI.

WOOD STRAIN-INSULATOR.

No. 822,642.

Specification of Letters Patent.

Patented June 5, 1906.

Application filed August 7, 1905. Serial No. 273,188.

To all whom it may concern:

Be it known that I, THOMAS C. WHITE, a citizen of the United States, residing in the city of St. Louis, in the State of Missouri, have invented certain new and useful Improvements in Wood Strain-Insulators, of which the following is a full, clear, and exact description, reference being had to the accompanying drawings, forming part of this specification.

My invention relates to that class of wood strain - insulators commonly used in the strain, stay, or supporting wires sustaining overhead electrical conductors; and the invention has for its object to produce an insulator of the kind named in which the total strength of the wood will be retained and the wood be less subject to the ingress of moisture than in similar insulators heretofore in use.

A further object of the invention is to provide a more permanent and more tightly fitting union between the wood insulating portions of the insulator and the clips secured thereto.

In the production of wood strain-insulators as heretofore made it has been common practice to secure the clips to the wooden insulating portion of the insulators by driving wedges into the ends of the insulating portion to expand the wood in the clips and produce a tight union between the parts. In so doing the wedges separate the fiber of the wood and act with a crushing or breaking effect thereon which renders the wood much more susceptible to the ingress and absorption of moisture into its texture, thereby permitting rapid decay of the wood and greatly diminishing the durability of the insulators. By my improvement I overcome these difficulties and produce a much more durable insulator.

Figure I is in part a side view and in part a longitudinal section of my insulator. Fig. II is a view of one of the end portions of the wood body of my insulator. Fig. III is a longitudinal section taken through one of the clips. Fig. IV is a cross-section taken on line $y-y$, Fig. I, with the wood body omitted. Fig. V is a side view of one of the clips with the members thereof separated. Fig. VI is a plan view of one of a pair of the clip-sections. Fig. VII is a plan view of the clip-section mating with that shown in Fig. VI. Fig. VIII is a similar view to Fig. I, illustrating a modification of the clip secured to the wood

body of the insulator. Fig. IX is a face view of one of the clips of modified form. Fig. X is a longitudinal section taken on line $v-v$, Fig. IX. Fig. XI is a transverse section taken on line $X-X$, Fig. VIII.

1 designates the wood body of my insulator, which terminates at each end in a conical portion 2, the bases or greatest diameters of the conical portions being at their outer extremities, from which points they taper or narrow inwardly to the junctions with the central portion of the wood body. The clips secured to the conical portions at the ends of the wood body of the insulator consist of pairs of sections or halves that are composed of semiconical sleeve portions 3 and 3', shaped to correspond to segments of the conical portions of the wood body and applied to said portions so as to mate thereon and fit circularly around them and against their bases. One of the clip-sections—as, for instance, that 3'—is provided with an ear 3^a, projecting from its outer end and which carries a tongue 5. The mating clip-section 3^b is provided with an ear 3^b, that receives the engagement of the tongue 5, the said ear being preferably apertured for the passage of said tongue therethrough, as seen in Figs. I and III. In attaching the sections to each other the tongue 5 is adapted to be bent over onto the ear 3^b in connection with each pair of clip-sections. The clip-sections are also united at their sides by the tongues 5^b, that are carried by flanges at the sides of one of each pair of sections and which are secured to side flanges of the mating clip-sections, preferably by passing the tongues 5^b through apertures in the side flanges of clip-sections opposing those by which the tongues are carried, as seen in Figs. I and IV. The apertures through which the tongues 5 and 5^b pass are indicated at 5^a. Projecting inwardly from the inner faces of the sleeve portions of the clip-sections are spurs 6, which are adapted to penetrate the conical portions of the wood body of the insulator to serve as a means of preventing turning of the clips upon the conical portions. Each of the clip-sections is provided with a loop 7, which is adapted to mate with a corresponding loop of the mating clip-section, to thereby provide eyes for the connection of the stays, guys, or strain-wires to the insulator.

In Figs. VIII to XI, I have shown a modification in which the clip-sections of the insulator and the wood body are of the same

shape as those previously described, corresponding numerals being employed in designating the parts. The only difference between the construction in the modification 5 and the previously-described construction is that in lieu of the tongues securing the clip-sections together in mating pairs I utilize rivets 5', by which the sections are held assembled when applied to the conical portions 10 of the wood body of the insulator.

I claim—

1. In a wood strain-insulator, the combination of a wood body having conical portions at its ends and clips consisting of pairs 15 of sections secured to said conical portions, substantially as set forth.

2. In a wood strain-insulator, the combination of a wood body having conical portions at its ends, the bases of which are disposed outwardly from the central portion of 20 said body, and pairs of clip-sections having sleeve portions secured to said conical portions substantially as set forth.

3. In a wood strain-insulator, the combination of a wood body having conical portions at its ends, the bases of which are disposed outwardly from the central portion of 25 said body, and pairs of clip-sections having sleeve portions secured to said conical portions and having eye-loops, substantially as set forth.

4. In a wood strain-insulator, the combination of a wood body having conical portions at its ends, the bases of which are disposed outwardly from the central portion of 35 said body, and pairs of clip-sections having sleeve-sections secured to said conical portions; said sleeve portions being provided upon their inner faces with spurs, substantially as set forth.

5. In a wood strain-insulator, the combination of a wood body having conical portions at its ends, the bases of which are disposed outwardly from the central portion of 40 said body, and pairs of clip-sections having sleeve portions corresponding in contour to segments of said conical portions and adapted to embrace said conical portions, substantially as set forth.

nation of a wood body having conical portions at its ends, the bases of which are disposed outwardly from the central portion of said body, and pairs of clip-sections having 45 sleeve portions corresponding in contour to segments of said conical portions and adapted to embrace said conical portions, substantially as set forth.

6. In a wood strain-insulator, the combination of a wood body having conical portions at its ends, pairs of clip-sections having sleeve portions fitted to said conical portions and having contours corresponding to segments of said portions; and means for uniting 50 said clip-sections in mating pairs, substantially as set forth.

7. In a wood strain-insulator, the combination of a wood body having conical portions at its ends, pairs of clip-sections having 55 sleeve portions fitted to said conical portions and having contours corresponding to segments of said conical portions; said sections being provided with tongues and slots for securing the mating pairs of clip-sections to each other, substantially as set forth.

8. In a wood strain-insulator, the combination of a wood body having conical portions at its ends, pairs of clip-sections having sleeve portions fitted to said conical portions 70 and having contours corresponding to segments of said conical portions; said clip-sections being provided with tongues and slots for securing the mating pairs of clip-sections to each other, and spurs projecting from the inner faces of said sleeve portions and adapted to enter into said conical portions, substantially as set forth.

THOS. C. WHITE.

In presence of—

NELLIE V. ALEXANDER,
E. S. KNIGHT.
